MATERNITY GARMENT ENSEMBLE

Elsie Frankfurt and Edna Ravkind, Dallas, Tex.

Application June 3, 1938, Serial No. 211,653

1 Claim. (Cl. 2-76)

Our invention relates to improvements in garments and more particularly to a maternity garment ensemble.

One of the principal objects of our invention is to provide a garment ensemble which is adjustable as to size so that the same is readily adapted to fit persons of different sizes or persons undergoing physiological development and is valuable as a maternity dress.

Another object of our invention is to provide an ensemble of the above described character having a blouse so constructed and arranged as to be self-adjusting to conform to the size of the skirt and at the same time forming a concealing means for the upper section of the skirt.

A further object of our invention is to provide an ensemble of the above described character provided with a skirt so arranged and constructed as to be readily adjustable to accommodate varying sizes of the waist of a wearer and further equipped with means to allow freedom of the abdomen.

A still further object of our invention is to provide an ensemble of the above described character which is simple in construction, economical in manufacture and pleasing in appearance.

A special object of our invention is to provide an ensemble of the above described character so constructed and arranged as to camouflage the physiological condition of an expectant mother.

Other objects and advantages will be apparent from the following description, appended claims and annexed drawings.

Referring to the drawings wherein like reference characters designate like parts throughout the several views:

Figure 1 is a front elevation of an ensemble constructed in accordance with the present invention.

Figures 2 and 3 are front and rear elevations of the blouse respectively.

Figures 4 and 5 are front and rear elevations of the skirt of the ensemble respectively.

Figure 6 is a rear elevation of the skirt broken away to illustrate the rear face of the front thereof in one of the extended positions.

Figure 7 is a detail sectional view taken on the line 1-1 of Figure 6.

Figure 8 is a detail sectional view taken on the line 8-8 of Figure 4.

Figure 9 is a detail sectional view taken on the line 9-9 of Figure 6.

Figure 10 is a detail sectional view taken on the line 10-10 of Figure 2.

In practicing our invention we provide an en-

semble 5 comprising a blouse 6 and skirt 7. The blouse is fashioned with a yoke 8, sleeves 9, and lower body portion 10, the front of which is provided with a plurality of downwardly extending kick or swing pleats 11 from the yoke to its lower edge, whereby to readily adjust the contour of the front to the shape of a wearer, while the back is provided with a central pleat extending from the yoke to its lower edge, as shown in Figure 3.

The front of the skirt is recessed from its upper edge for a considerable portion of its length to provide a substantially rectangular shaped opening 12 to allow adjustment for and freedom of the abdomen and the waistband is provided with a pair of straps 13 to be tied or otherwise adjustably connected together in bridging relation across the top of the opening, for securing the skirt about the waist of a wearer. Centrally thereof, the front of the skirt is provided with an inner box pleat 14 which extends from the lower edges of the opening 12 to the lower edge of the skirt and said pleat is provided with relatively wide laterally inwardly extending folded sections 15 stitched to the face of the skirt by rows of stitches 16 which are to be changed from time to time during the development of the wearer, from the position of Figure 4 to that of Figure 6 to vary the width of the skirt and thereby bring about proper fitting thereof at all times during pregnancy.

Secured to the upper edge of the pleat 14 adjacent the lower edge of the opening 12 is an upwardly extending strap 17 terminating at the upper end in a loop 18 embracing one of the horizontally disposed straps 13 whereby to support and adjust the front of the skirt relative to the waist of the wearer, the adjustable feature being brought about by sliding the loop on the strap 13 and by varying the length of the strap 17 through the medium of the loop that can be stitched to the body of the strap 17 at any place along the length thereof, as will be apparent upon inspection of Figure 7. When the ensemble is worn, the lower section of the body portion 10 of the blouse is of a sufficient length to extend downwardly over the skirt and conceal the opening 12 thereby presenting a neat and tidy appearance and due to the swing pleats 11 the lower section of the blouse lies full over the skirt and serves to camouflage the physiological condition of the wearer.

What we claim is:

In a maternity garment ensemble, a blouse including a body portion, swing pleats in the front of the body portion and extending to the lower edge thereof, a skirt including a waistband and

having a front thereof centrally recessed from its upper edge to provide an abdominal receiving opening, said body portion being of a length to conceal said opening, straps each having one of their ends secured to the waistband and adapted to be adjustably connected at their opposite ends for the disposal of the straps in bridging relation across the top of the opening to secure the skirt to the wearer, a stitched box pleat on the inner surface of the front of the skirt and ex-

tending centrally thereof from the opening to the lower edge of the skirt, a strap looped about one of the first straps for adjustable connection thereto and depending therefrom with its lower edge secured to the upper edge of the box pleat 5 and said box pleat being adjustable from end to end by changing the stitching thereof whereby to vary the width of the skirt.

ELSIE FRANKFURT.
EDNA RAVKIND.
